UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

NEUTRALIZING INDUCTIVE DISTURBANCES.

1,120,992.

Specification of Letters Patent.

Patented Dec. 15, 1914.

Application filed April 2, 1913. Serial No. 758,371.

To all whom it may concern:

Be it known that I, ERNST F. W. ALEXANDERSON, a citizen of the United States, residing at Schenectady, in the county of Schenectady, State of New York, have invented certain new and useful Improvements in Neutralizing Inductive Disturbances, of which the following is a specification.

My invention relates to alternating current systems of distribution, and particularly to electric railway systems which employ alternating current.

When a low voltage conductor, such as a telegraph or telephone wire, extends in close proximity to a conductor carrying single phase alternating current, the low voltage conductor is subject to disturbances due to induction, both static and magnetic. Thus in the case of a single phase alternating current railway system a telegraph or telephone wire on the same poles with, or in the immediate vicinity of, the railway conductor is subject to such disturbances. The disturbances due to magnetic induction can be largely avoided by providing a return conductor for carrying the current back to the supply station instead of returning such current to the station through the rails. The difficulty to be overcome in the use of a return conductor is to satisfactorily direct the current from the rails into the return conductor so that the inductive effect of the current flowing in the return conductor will neutralize the inductive effect of the current flowing in the trolley wire at substantially every point in the system.

The object of my invention is to provide means for neutralizing more perfectly than has heretofore been done the inductive disturbances produced in low voltage conductors by single phase alternating current systems.

More particularly the object of my invention is to provide means for directing the current, which normally tends to flow in the rails of an electric railway system, into a return conductor, so that the inductive effects of the trolley wire, or outgoing conductor, and the return conductor are opposite and substantially equivalent, and hence neutralize each other at all points in the system.

I accomplish the object of my invention by providing a return conductor inductively

interlinked with the trolley-wire so that substantially the same amount of current is maintained in adjacent portions of both conductors. I then establish reactive connections between the rails and the return conductor so as to properly direct the flow of the working current of the apparatus operating on the system from the rails to the return conductor. These reactive connections are designed to maintain a potential relation between the rails and the return conductor of such magnitude and direction that the working current of the apparatus is directed from the rails to the return conductor through two paths, and are further designed to proportion the distribution of current between these paths inversely as the distance of the apparatus from the reactive connections.

The novel features which I believe to be patentably characteristic of my invention are definitely indicated in the claims appended hereto.

The features of construction and the mode of operation of my invention will be understood by reference to the following description taken in connection with the accompanying drawings, in which:—

Figure 1 is a diagrammatic view of a railway system, embodying my invention; Fig. 2 is a similar view showing a preferred form of my invention; and Fig. 3 is a graphic representation of the voltages of the main conductors of the system.

Referring first to Fig. 1 of the drawings, I have illustrated an electric car 5 arranged to run on rails 6, only one side of the track being shown. The car is provided with a trolley of any desired type which operatively engages the overhead trolley-wire 7. It will be understood that the type of electric car which I have shown in the drawings is purely for the purpose of illustration, since any other form of electric railway apparatus, as for example, an electric locomotive, may be operated on the system. The system is supplied with alternating current from any desired source. A conductor 8 is arranged parallel to and in the immediate vicinity of the trolley-wire 7. For convenience, I shall hereafter refer to the trolley-wire 7 as the outgoing conductor and the conductor 8 as the return conductor. It will be obvious, however, that with an alternat-

ing current the direction of flow of current in each conductor will be reversed each half cycle, and hence the terminology adapted is not strictly accurate, although sanctioned by usage. A low voltage telephone or telegraph conductor 9 is located near the trolley wire 7 and the arrangement of my system is to neutralize the inductive effect of the trolley-wire on the low voltage conductor, so that this conductor will not be subject to objectionable inductive disturbances. The outgoing conductor 7 is divided into sections of a predetermined length and adjacent sections are connected in series through the primary winding 10 of a transformer. The return conductor is similarly divided into sections which are similarly connected through the secondary windings 11 of the transformers. Reactances 12 connect the rails 6 to the return conductor, and these reactances are located near to and on each side of each transformer. I preferably provide one or more intermediate reactive connections 13 between the rails and the return conductor. A current flowing in the outgoing conductor 7 will, in flowing through the primary winding 10 of the transformer, induce a certain current in the secondary winding 11 of the transformer, and this induced current will tend to flow through the return conductor 8. The secondary winding of the transformer has the same number of turns as the primary winding, and hence the current flowing in the secondary winding will be substantially the same as that flowing in the primary winding. The reactances 12 and 13 provide two paths for the flow of the working current employed to operate a car 5, or other apparatus, from the rails to the return conductor. When a car is operating on a part of the system between a reactance 12 and a reactance 13, a portion of the working current will flow from the rails to the return conductor through reactance 12 and the remainder of the current will similarly flow through reactance 13. The reactances are so designed that the ratio of the amounts of current flowing in these respective paths is inversely proportional to the distances of the car from the reactances. The reactances are further designed to become magnetically saturated when a predetermined current flows therethrough. While magnetically saturated the impedance of the reactance is relatively low, that is, the impedance of the reactance to the flow of current in excess of the predetermined amount required to produce saturation is low compared to the impedance of the reactance to the flow of the predetermined current itself. The inductance of each reactance and the predetermined current required to produce magnetic saturation of the reactance are proportioned to establish the proper and desired potential relations between the rails and the return

conductor and also to provide a path of relatively low impedance to the flow of the greater portion of the working current of each apparatus.

It will be noticed that the arrangement of the reactances 12 in Fig. 1 of the drawings amounts substantially to shunting the secondary winding of each transformer by an inductive winding and connecting the middle point of the latter winding to the rails. It will be evident that the same result can be obtained by eliminating this inductive winding and connecting the middle point of the secondary winding of each transformer to the rails. This arrangement is illustrated in Fig. 2 of the drawings and constitutes a preferred embodiment of my invention. In the arrangement of this figure the middle point of the secondary winding 11 of each transformer is connected to the rails 6 through conductors 14. The conductors 14 and the reactances 13 thus provide two paths for the flow of the working current of any apparatus, operating between a conductor and a reactance, from the rails to the return conductor. The reactances and transformers are so designed that the current will divide between these paths inversely as the distance of the car from the points of connection between the rails and the return conductor.

The potential relations of the conductors of my improved system will be understood by reference to Fig. 3 of the drawings. The supply station is assumed to be located on the left of the figure. The horizontal line A represents the voltage of the rails which is that of the ground, and consequently zero. The dotted line B represents the voltage of the outgoing conductor when no transformers are employed, and the line C represents the voltage of the outgoing conductor in my system when transformers are used, as hereinbefore described. The dotted line D represents the voltage of the return conductor, provided the current was returned entirely through such conductor without any ground or rail connections. The line E represents the voltage in the return conductor of my improved system. At about the middle portion of each section of the return conductor the voltage of the conductor is substantially zero and this point is connected through a reactance 13 to the rail. The adjacent ends of the adjacent sections of the return conductor are connected in series through the secondary windings 11 of the transformers, and the potential difference between these ends is equal to the potential drop in the secondary winding. The middle portion of each secondary winding is connected to ground, either directly as in Fig. 2, or indirectly by means of the shunting reactances as in Fig. 1, and therefore one end of each section of the return conductor will be at a higher potential than

ground and the adjacent end of the adjacent conductor will be at a lower potential than ground. The current in the rails will, therefore, flow from the rails to that section 5 of the return conductor whose end is at a lower potential than the ground.

It will be noticed from an inspection of Figs. 1 and 2 of the drawings that two paths are provided for the flow of the working current from the rails to the return conductor. Since the reactive connections between the rails and the return conductor are preferably magnetically saturated by a small portion of the working current, the 10 impedance of these paths is relatively low for the remainder of the working current, and due to the potential relations maintained between the rails and the return conductor such current will readily flow from 15 the rails to the return conductor.

The particular advantage of my system results from the use of the reactive connections between the rails and the return conductor. The use of this character of connection provides a convenient and efficient means for maintaining the proper potential relations between the rails and the return conductor. At the same time the magnetic characteristics of the reactive connections 25 can be so designed that the current carried by the rails from the operating apparatus to the adjacent reactive connections will 30 divide in approximately inverse proportion to the distance of such apparatus from the 35 respective reactive connections, whereby the inductive effect of these currents is completely neutralized.

It will be obvious to those skilled in the art that my invention can be carried out by 40 various arrangements differing in form from those herein illustrated and described. I do not therefore, desire to limit myself to the particular construction or arrangement herein shown, but aim in the appended claims to 45 cover all modifications which are within the scope of my invention.

What I claim as new and desire to secure by Letters Patent of the United States is:—

1. An electric railway system comprising 50 in combination rails forming a continuous conductor, an outgoing conductor, a return conductor, transformers each having a primary winding and a secondary winding, one winding of each transformer being connected in series with the outgoing conductor and the other winding of each transformer being connected in series with the return conductor, and means for establishing reactive connections between the rails and the 55 return conductor at points near the transformers.

2. An electric railway system comprising 60 in combination rails forming a continuous conductor, apparatus to be operated on said system, an outgoing conductor, a return con-

ductor, transformers each having a primary winding and a secondary winding, one winding of each transformer being connected in series with the outgoing conductor and the other winding of each transformer being connected in series with the return conductor, and means for establishing reactive connections between the rails and the return conductor, said reactive connections providing two paths for the flow of the working 75 current of any operating apparatus from the rails to the return conductor.

3. An electric railway system comprising in combination rails forming a continuous conductor, apparatus to be operated on said 80 system, an outgoing conductor, a return conductor, transformers each having a primary winding and a secondary winding, one winding of each transformer being connected in series with the outgoing conductor and the 85 other winding of each transformer being connected in series with the return conductor, and means for establishing reactive connections between the rails and the return conductor, said reactive connections providing two paths for the flow of the working 90 current of any operating apparatus from the rails to the return conductor and adapted to proportion the distribution of current 95 between these paths inversely as the distance of the apparatus from the reactive connections.

4. An electric railway system comprising in combination rails forming a continuous conductor, apparatus to be operated on said 100 system, an outgoing conductor, a return conductor, transformers each having a primary winding and a secondary winding, one winding of each transformer being connected in series with the outgoing conductor and the 105 other winding of each transformer being connected in series with the return conductor, and means for establishing reactive connections between the rails and the return conductor at points near the transformers, said reactive connections offering paths of relatively low impedance to the 110 flow of the working current of the apparatus from the rails to the return conductor.

5. An electric railway system comprising 115 in combination rails forming a continuous conductor, apparatus to be operated on said system, an outgoing conductor, a return conductor, transformers each having a primary winding and a secondary winding, one 120 winding of each transformer being connected in series with the outgoing conductor and the other winding of each transformer being connected in series with the return conductor, and means for establishing reactive 125 connections between the rails and the return conductor, said reactive connections maintaining potential relations between the rails and the return conductor of such magnitudes and directions that the working cur- 130

rent of any apparatus is directed from the rails into the return conductor through two paths.

6. An electric railway system comprising in combination rails forming a continuous conductor, apparatus to be operated on said system, an outgoing conductor, a return conductor, transformers each having a primary winding and a secondary winding, one winding of each transformer being connected in series with the outgoing conductor and the other winding of each transformer being connected in series with the return conductor, and means including the secondary winding of said transformer for establishing a reactive connection between the rails and the return conductor, said reactive connection being designed to become magnetically saturated when the working current of any operating apparatus flows therethrough.

7. An electric railway system comprising in combination rails forming a continuous conductor, an outgoing conductor, a return conductor, transformers each having a primary winding and a secondary winding, the primary winding of each transformer being connected in series with the outgoing con-

ductor and the secondary winding of each transformer being connected in series with the return conductor, and means electrically connecting the middle point of the secondary winding of each transformer to the rails.

8. An electric railway system comprising in combination rails forming a continuous conductor, an outgoing conductor, a return conductor, transformers each having a primary winding and a secondary winding, the primary winding of each transformer being connected in series with the outgoing conductor and the secondary winding of each transformer being connected in series with the return conductor, means electrically connecting the middle point of the secondary winding of each transformer to the rails, and an inductive reactance located between adjacent transformers and connecting the rails to the return conductor.

In witness whereof, I have hereunto set my hand this 1st day of April 1913.

ERNST F. W. ALEXANDERSON.
